SHEET FEEDING AND TRIMMING
MECHANISM

Edward R. Kast and John H. McElroy, Pearl River, N. Y., assignors to Dexter Folder Company, New York, N. Y., a corporation of New York

Application March 24, 1931. Serial No. 524,960

68 Claims. (Cl. 164—48)

This invention relates to sheet feeding mechanism, and while capable of general use, is particularly adapted for feeding sheets to mechanism for trimming the same.

5 In the trimming of sheets of money, for example, the sheets, each having a plurality of notes printed thereon, have heretofore been hand fed one after another to mechanism for trimming them around their four sides preparatory to numbering and sealing the individual notes and cutting the same from the sheets. Each sheet fed to the trimming mechanism in this manner, is sight registered therewith, and the trimming mechanism has been manually controlled to trim the sheet after registration of the same as stated. The trimming mechanism being manually controlled, there has been no requirement for the attendant to feed and sight register the sheets at any particular rate of speed, and the amount of work produced has therefore been governed, on the one hand, by the inclination of the attendant to work quickly or slowly, and limited on the other hand, by manual operations involved in the method above referred to.

20 One object of this invention is to provide sheet feeding mechanism which eliminates the aforesaid defects and disadvantages and automatically feeds and controls a money or other sheet trimming machine so as to materially increase the output thereof.

25 Another object of this invention is to provide sheet feeding mechanism which automatically feeds and automatically controls a money or other sheet trimming mechanism and relieves the attendant from the constant strain and fatigue incident to manual operations heretofore necessary in connection with money or other sheet trimming machines.

30 Another object of this invention is to provide mechanism which automatically feeds and controls a money trimmer and requires the attendant to sight register the sheets with said trimmer as fast as they are delivered thereto by said mechanism.

35 Another object of this invention is to provide mechanism which automatically feeds and controls a money or other sheet trimmer and may be gradually speeded up to increase production without the attendant's knowledge.

40 Another object of this invention is to provide feeder operated sheet stops for a sheet trimmer that materially reduce the time required to register the sheet therewith.

45 Another object of this invention is to provide a feeder operated device which enables waste

trimmed from the sheets to be cleared from the path of travel of untrimmed sheets to the trimmer.

Another object of this invention is to provide feeder operated sheet supporting means movable in one direction to deliver sheets to a trimmer and in the opposite direction to facilitate removal of waste from sheets trimmed by said trimmer.

Another object of this invention is to provide sheet feeding and delivery devices for a sheet trimmer associated directly therewith and operated in conjunction with an automatic feeder therefor.

Another object of this invention is to provide improved sheet stops and improved sheet feeding and drop rollers for an automatically fed sheet trimmer.

Another object of this invention is to provide sheet controlled means associated with the trimmer and controlling the operation of an automatic sheet feeder therefor.

Another object of this invention is to provide cooperating control mechanisms for both a sheet trimmer and an automatic sheet feeder therefor.

These and other objects of this invention will appear as the following description thereof proceeds, and in order to more clearly understand said invention reference may be had to the accompanying drawings which illustrate one embodiment of the inventive idea.

In said drawings:

Figs. 1 and 1a are complementary side views of interconnected sheet feeding, sheet trimming, and sheet delivery mechanisms embodying the present invention;

Figs. 2 and 2a are complementary top plan views, with parts omitted, of the mechanisms shown in Figs. 1 and 1a;

Fig. 3 is an enlarged detail perspective view of the main cam shaft, a detector device, drop rollers, a movable sheet support, a clutch for the sheet feeding mechanism, and driving connections for these instrumentalities;

Fig. 4 is a detail perspective view of a pile elevator forming part of the sheet feeding mechanism;

Figs. 5 and 6 are enlarged detail perspective views of feed and drop rollers associated with the sheet feeding mechanism and the sheet trimming mechanism, respectively;

Fig. 7 is an enlarged detail perspective view, with parts omitted, of the upper portion of the sheet trimming mechanism;

Fig. 8 is a detail perspective view of the clutch for the sheet trimming mechanism;

Fig. 9 is an enlarged detail perspective view, with parts omitted, of the clutch for the sheet feeding mechanism, the movable sheet support, and the lower portion of the sheet trimming mechanism;

Fig. 10 is an enlarged vertical longitudinal sectional view of the sheet trimming table or die plate; and

Fig. 11 is an enlarged detail perspective view of sheet stops for the trimming mechanism and feeder controlled operating means for said stops.

Referring to the drawings, wherein like reference characters designate like parts throughout the several views, 5 indicates a machine foundation on which is bolted or otherwise suitably secured, as at 6, 6, a bed plate 7 (Figs. 1 and 1a). This bed plate, in turn, has bolted or otherwise suitably secured thereto, as at 8, 8, a support 9 for an electric motor 10. The motor 10 is supplied with current from any suitable source through leads 11 enclosed in a suitable flexible conduit 12 and connected with said source and said motor in any suitable manner. The motor is controlled by a suitable switch (not shown), and said motor is bolted or otherwise suitably secured, as at 13, 13, on the support 9. The armature shaft 14 of the motor 10, has fixed thereon a bevel gear 15 (Figs. 2 and 3) which meshes with a bevel gear 16. The bevel gear 16 is fixed on a short shaft 17 that extends at right angles to the armature shaft 14 and is journaled in suitable bearings in a housing 17' that is bolted or otherwise suitably secured at 17" on a pedestal 18. The pedestal 18 supports the sheet trimming mechanism, to be hereinafter described, and the base 18' of said pedestal is bolted or otherwise suitably secured, as at 19, 19, to the bed plate 7.

Fixed on the shaft 17 is a worm pinion 20 (Fig. 3) which meshes with a worm gear 21 that is fixed on a short shaft 22. Pinion 20 and gear 21 are enclosed in housing 17', and shaft 22 extends at right angles to shaft 17 through said housing and is journaled in suitable bearings thereon. Fixed on the shaft 22 is a sprocket 23 around which passes a chain 24 that also passes around a sprocket 25. This sprocket 25 is fixed on a stub shaft 26 journaled in a suitable bearing on an arm 27 (Fig. 1a) which is bolted or otherwise suitably secured at 28 to one of the side frames 29 of the sheet feeding mechanism. The side frames 29 are bolted or otherwise suitably secured, as at 30, 31, to short and long vertical standards 32 and 33, respectively. The standards 32, 33 are anchored in sockets 34 secured to, or formed integrally with, plates 35 that are bolted or otherwise suitably secured at 36, 36 to the machine foundation 5.

Fixed on the stub shaft 26 is a sprocket 37 (Figs. 3 and 4) around which passes a chain 38. This chain 38 also passes around a sprocket 39 that is fixed on a shaft 40. The shaft 40 is journaled in suitable bearings on side plates 41 carried by stay shafts 42, 43 that connect the side frames 29 of the sheet feeding mechanism together. Fixed on the shaft 40 is a pinion 44 that meshes with a gear 45. This gear 45 is fixed on a stub shaft 46 that is journaled in any suitable manner on one of the side plates 41. Keyed to, and slidably along, the stub shaft 46 is a clutch member 47 (Fig. 3) adapted to engage a clutch member 48 through the action of spring 49 that is carried on the stub shaft 46 and nor-

mally tends to urge the clutch member 47 into engagement with the clutch member 48. The clutch member 48 is secured to or formed integrally with a gear 50 that is loosely mounted on the stub shaft 46 and retained against endwise displacement thereon in any suitable manner.

Journaled in suitable bearings in the side plates 41 is a rockshaft 51 on which is rigidly secured, as at 52, a bell crank 53. This bell crank 53 is provided with a handle 54 and an arm 55, said arm having an enlarged end 56 to which are rigidly secured clutch spreading pins 57. The shaft 51 may be rocked manually by the handle 54, or said shaft may be rocked automatically by means hereinafter described. In either case, said shaft, when rocked in a clockwise direction as viewed in Fig. 3, causes the arm 55 to bring the pins 57 between the clutch members 47, 48 to disconnect them and prevent driving of the gear 50 through the clutch, the shaft 46, and the described connections therefor with the motor 10. When the shaft 51 is rocked in the opposite direction, however, the spreader pins 57 are removed from the clutch members 47, 48, whereupon the spring 49 engages the clutch member 47 with the clutch member 48 to drive the latter and the gear 50. This clutch controls the operation of sheet feeding mechanism, hereinafter described, and serves to establish a drive therefor with the motor 10, as follows.

The gear 50 meshes with a pinion 58 (Fig. 4) that is secured to or formed integrally with a short shaft 59. This shaft 59 is journaled in suitable bearings on one of the side plates 41, said shaft having secured thereto a gear 60. The gear 60 meshes with a pinion 61 that is fixed on a short shaft 62 journaled in suitable bearings on the side plate 41 that carries the short shaft 59. Fixed on the shaft 62 is a pinion 63 that meshes with a gear 64 secured on a stub shaft 65 which is journaled in the side plate 41 that carries the shafts 59 and 62. This stub shaft 65 has secured thereto a pinion 66 which meshes with a gear 67 that is fixed on a main cam shaft 68 extending transversely of the machine and journaled in suitable bearings on the side frames 29 of the sheet feeding mechanism. The sheet feeding mechanism includes a pile elevator which is preferably operated, controlled, and constructed as follows.

Mounted loosely on the shaft 68 is a cam 69 (Fig. 4) which is rigidly connected with the gear 67, as by a pin and slot connection 70, 71, that provides for angular adjustment of this cam on said shaft. The cam 69 is adapted to engage a roller 72 journaled on an arm 73 which is fixed on a short shaft 74. This shaft 74 is journaled in suitable bearings on one of the frames 29, and said shaft and the arm 73 thereon are spring operated in one direction and cam operated in the opposite direction as will hereinafter appear. Fixed on the rockshaft 74 is an arm 75 the free end of which is pivotally connected with one extremity of a link 76. The opposite extremity of the link 76 is pivotally connected with a pawl carrying arm 77 loosely mounted on a shaft 78 extending transversely of the frames 29 and journaled in suitable bearings therein. Pivoted on the free end of the arm 77 is a pawl 79 which is adapted to engage a ratchet 80. Said ratchet is loosely mounted on the shaft 78 between one of the frames 29 and a clutch member 81 fixed on said shaft. The ratchet 80 is provided with a clutch member 82 normally engaging the clutch member 81 and 1

acting therethrough to drive the shaft 78 when the ratchet 80 is turned in one direction by the pawl 79. Turning movement of the ratchet in the opposite direction is prevented by a pawl 83 5 that engages the teeth of the ratchet and is pivoted on the frame 29 adjacent thereto.

Fixed on the shaft 78 are worms 84 which mesh with worm gears 85 that are rigidly secured on the front ends of a pair of shafts 86. These 10 shafts 86 extend longitudinally of the machine in spaced parallel relation and are journaled in suitable bearings on the frames 29. The shafts 86 have fixed thereon sprockets 87 around which pass chains 88 that also pass around sprockets 15 89. The sprockets 89 are fixed on shafts 90 extending longitudinally of the machine below the shafts 86 and journaled in suitable bearings on the sockets 34. The chains 88 run over suitable guides (not shown) and comprise an elevator for a pile of sheets 91 elevated by said 20 chains as said sheets are successively separated and forwarded from the top of said stack by sheet separating and forwarding devices to be presently described. The elevator is operated, as 25 aforesaid, by the described driving connections therefor with the spring and cam operated rock arm 73. The pile of sheets 91 is supported on a board 92 which, in turn, is supported by one of several pairs of flights 93 secured in spaced parallel 30 relation on the chains 88.

Any suitable means may be employed to automatically control the upward feeding of the pile of sheets 91 by the elevator 88, but as herein shown said means is preferably of the type disclosed in application Serial No. 158,770, C. E. 35 Christophe, filed January 3, 1927. This control means (Fig. 4) includes a detector 94 and a control member 95 automatically controlling the drive for the elevator. The detector 94 is continuously moved toward and away from the pile 40 of sheets 91 and when a sufficient number of sheets have been fed off the top of said pile, the detector lowers sufficiently to disengage a hook 45 96 from a projection 97 on the control member 95. The control member is then urged forwardly by a spring pressed rod 98 so that the roller 72 follows the cam 69 which then acts on said roller to operate the drive for the elevator and lift the 50 pile of sheets. When the sheets are lifted to proper height, the detector 94 is also lifted and acts through its shaft 99 and an arm 100 thereon, to pull a spring 101 and swing a lever 102 upwardly to reengage the hook 96 carried thereby with the projection 97 on the control member 95. 55 The roller 72 is thus prevented from following the cam 69 and the drive for the elevator is therefore no longer operated. The cam 69, however, intermittently engages the roller 72 and acts, together with the spring pressed rod 98, 60 to raise and lower the detector 94 while the drive for the elevator is thrown out of operation.

When the drive for the elevator is operating, the hook 96, which at this time is disengaged from the projection 97, is acted upon by a cam 65 103 on the control member 95. The cam 103 and the spring 101 act to raise and lower the detector 94 during elevation of the pile of sheets, and this continuous operation of the detector during 70 elevation of the pile ensures against interference with the continuous operation of the sheet forwarding device above referred to. The cam 103 is formed on the control member 95 adjacent a bent portion 104 thereof that rides on a pin 105 secured to one of the frames 29 and acting to 75 prevent excessive downward movement of said

control member. Excessive upward movement of the lower end of lever 102 is prevented by a pin 106 that projects over said lever from the adjacent frame 29 and is secured thereto in any suitable manner.

80

The elevator is provided with means for manually operating it to raise and lower the pile of sheets, and as herein shown, said means is preferably of the type disclosed in the application of John H. McElroy, Serial No. 380,078, filed July 23, 1929. This manually operated means includes the shaft 78 which is slidable transversely of the frames 29, a handle 107 fixed on the shaft 78 and having a cam 108 for engagement with the roller 109 extending radially therefrom, a spring 110 carried by the shaft 78 and having one end secured thereto and an opposite end bearing against the adjacent frame 29, the aforesaid devices acting, upon operation of the handle 107, to slide the shaft 78 and engage and disengage the clutch parts 81, 82 so that the shaft 78 may be operated automatically or manually, as desired, to operate the elevator.

85

The sheet separating devices, above referred to, are preferably of the type disclosed in Patent No. 1,475,621, granted November 27, 1923 to C. E. Christophe. These devices include a driven combing wheel 111, a hollow foot clamp 112, and a suction sheet separator 113 (Fig. 1a). The driven combing wheel 111 effects a preliminary separation of topmost sheets of the pile, the foot clamp 112 clamps the remaining sheets and serves to blow air between them and the sheets thereabove, and the separator 113 acts to successively separate the sheets from the top of the pile. These devices may, if desired, be duplicated at opposite rear corners of the pile and said devices are preferably operated and mounted as follows. Fixed on the shaft 62 is a gear 114 (Fig. 4) which meshes with an idler gear 114' 115 journaled on one of the frames 29. The idler gear 114' meshes with a gear 115 that is fixed on a shaft 116. The shaft 116 is journaled in suitable bearings on the frames 29, and the gear 115 has compounded therewith a bevel gear 117 which 120 meshes with a similar gear 118. The gear 118 is fixed on a short vertical shaft 119 journaled in suitable bearings in a housing 120 (Fig. 1a) secured to one of the frames 29. The shaft 119 has fixed thereon a bevel gear 121 which meshes 125 with a similar gear 122 that is fixed on a shaft 123. This shaft 123 is journaled in suitable bearings in the housing 120 and in a housing 124 that is carried by and adjustable along rods 125.

130

The rods 125, in turn, are carried by frames 126 mounted on the frames 29 at the tops thereof. Keyed to, and slidable along the shaft 123 with the housing 124 is a gear (not shown) which is enclosed in said housing and through other gears therein (not shown) serves to drive a shaft 127. 135 The shaft 127 and the housing 124 are supported on a cross member 128 which in turn supports a bracket 129 on which the sheet separating devices 111, 112, 113 are mounted and adjusted vertically by an adjusting wheel 130. The cross member 140 128 and the parts carried thereby are adjustable along the rods 125 which, for this purpose have rack teeth 131 engaged by a pinion 132 fixed on the axis of a hand wheel 133 which is journaled on the cross member 128 and serves to move the latter and the sheet separating devices along the rods 125 as aforesaid. The shaft 127 serves, through gearing (not shown), to drive the combing wheel 111 and a cam shaft 134 having a series of cams thereon (not shown) which raise and 145 150

lower the sheet separating devices as disclosed in Christophel Patent No. 1,475,621 above referred to.

Any suitable means may be employed to create suction in a conduit 135 and blow air through a conduit 136 (Fig. 1a). These conduits are connected with control mechanism which is preferably of the type disclosed in application Serial No. 260,123, filed March 8, 1928 by E. R. Kast.

- 10 This control mechanism is enclosed in a housing 137 mounted on one of the frames 29 and having air and suction connections 138, 139 with the hollow foot clamp 112 and the suction sheet separator 113, respectively. The mechanism in the 15 housing 137 controls the air in clamp 112 and the suction in separator 113 so that these devices act to blow air between and separate the sheets at the proper time for forwarding by suction sheet forwarding devices 140 (Figs. 1a and 4).
- 20 The mechanism in housing 137 also controls the production of suction in the devices 140 and for this purpose said housing is connected with said devices by a flexible conduit 141. The suction forwarding devices preferably have the same 25 construction and operation as disclosed in Patent No. 1,584,734, granted May 18, 1926, to C. E. Christophel.

Accordingly, there is fixed on the shaft 68 a cam 142 in the cam groove 143 of which is engaged a roller 144. This roller is journaled on an arm 145 that is loosely mounted on a stud 146 secured to a stationary part of the machine. The arm 145 has secured thereto or formed integrally therewith, a segmental arcuate-shaped 35 rack 147 that meshes with a pinion 148 fixed on a tube 149. The tube 149 is loosely mounted on a stay shaft 150 which extends transversely of the feeder and is secured to the side frames 29 thereof. Fixed on the tube 149 so as to be oscillated therewith by the rack 147 and the pinion 148, is an arm 151 that oscillates and reciprocates a bell crank lever one arm 152 of which is pivotally connected to the arm 151. Said bell crank lever is pivotally mounted at 153 on a carriage 45 154 which, through the arm 152 and the arm 151 is reciprocated along a substantially horizontal track 155. The track 155 is fixed on the stay shaft 150 substantially at the center of the pile elevator and in overhanging relation with the 50 forward top portion of the pile of sheets carried thereby. The other arm 156 of the bell crank lever is provided with a cam 157 that engages a roller 158 journaled on a lever 159. The lever 159 is pivoted at 160 on the carriage 154, and 55 during reciprocation of said carriage, the lever 159 is raised and lowered to impart like motion to the suction sheet forwarding devices 140. For this purpose, the lever 159 is provided with a forked end 161 which engages the underside of 60 a collar 162 that is fixed on a pipe 163 mounted for vertical sliding movement on the carriage 154. The upper end of this pipe 163 is connected with the flexible suction conduit 141, and the lower end of said pipe has branches 164 which 65 carry the forwarding devices 140.

The sheet separating and forwarding devices operate successively to separate and forward sheets from the top of the pile on the elevator, and as each sheet is forwarded, it is received between a feed roller 165 and drop rollers 166 (Figs. 3, 4 and 5) which feed the sheets across a movable support 167 to other feeding devices and a sheet trimming mechanism hereinafter described. The feed roller 165 is fixed on the shaft 70 116, and the drop rollers 166 are journaled on

80 arms 168 (Fig. 5). The arms 168 are fixed on a rockshaft 169 that is journaled in suitable bearings on the frames 29 and extends transversely thereof adjacent the feed roller 165. Fixed on the rockshaft 169 is an arm 170 having journaled thereon a roller 171 that engages a cam 172. The cam 172 is fixed on the cam shaft 68 and serves to rock the drop rollers 166 toward and away from the feed roller 165 so that said rollers open relatively to receive each sheet and thereafter close to feed it across the movable sheet support 167.

85 The movable sheet support 167 is pivotally mounted on studs 167' (Fig. 3), as by brackets 173 (Fig. 3) loosely receiving said studs and riveted or otherwise suitably secured to the support 167 adjacent the rear edge thereof. The studs 167' project inwardly from plates 41, and the sheets pass from the feed roller 165 to the support 167 over bridge pieces 167'' (Fig. 1a) which 90 are secured on the stay shaft 42. The support 167 is raised into alignment with a stationary trimming table or die plate 174 (Fig. 1) when the sheet is fed thereon as hereinafter described, and said movable support 167 is lowered when a trimmer 175 and cutters 175' thereon descend and trim the sheet and cut the trimming at diagonally opposite corners thereof, on said table or die plate. This lowering of the support 167 as the trimmer descends to trim the sheet, enables the 100 waste portions of the trimmed sheet to fall out of the path of travel of untrimmed sheets to the trimming mechanism and thus insure against jamming or obstruction of the sheets fed thereto.

105 The trimming mechanism, the sheet feeding 110 mechanism and the movable support 167 are operated in timed relation, and these devices are, for this purpose, preferably interconnected to insure synchronous operation of the same. The support 167 is preferably operated by a cam 115 176 (Fig. 3) that is fixed on the cam shaft 68. The cam 176 engages a roller 177 that is journaled on the short bent arm 178 of a bell crank 179 that has a long forwardly projecting arm 180. The bell crank 179 is loosely mounted on 120 the stay shaft 42 and retained against endwise displacement thereon by any suitable means for this purpose, and the free end of arm 180 carries a stud or pin 180' with which is connected one end of a spring 262 (Fig. 7). The opposite end 125 of spring 262 is connected with a hook 263 on a pedestal 231 of the trimming machine and said spring serves to maintain the roller 177 in engagement with cam 176 so that arm 180 is cam operated in one direction and spring operated in 130 the opposite direction by the sheet feeding mechanism. The arm 180 has pivotally connected therewith one end of a link 181 the opposite end of which is pivotally connected with an arm 182 that is fixed on a rockshaft 183. The rock- 135 shaft 183 is journaled in suitable bearings on arms 184 that are fixed on the stay shaft 42 in any suitable manner. Fixed on the rockshaft 183 is an arm, made in two parts, 185, 186 adjustably connected together as by a pin and slot 140 connection 187, 188. The arm 185, 186 is pivotally connected with a bracket 189 that is bolted or otherwise suitably secured to the support 167 on the under forward portion thereof. The bracket 189 has pivotally connected therewith 145 one extremity of a spring pressed rod 190 the opposite extremity of which is guided in a bracket 191 bolted or otherwise suitably secured to a stationary part of the sheet trimming mechanism. It will appear from the foregoing, that 150

the table or support 167 is rocked in one direction by arm 180 to enable the sheets to pass over the table to the trimming mechanism and that said table is rocked in the opposite direction by 5 said arm to facilitate clearing of waste portions of the trimmed sheets from the path of travel of untrimmed sheets to said mechanism.

The pedestal 18 has bolted or otherwise suitably secured thereto a column 192 (Fig. 1) on 10 the top of which is bolted the stationary table or trimmer die plate 174. As each sheet is fed across the bridge pieces 167' and the movable support 167 by the feed and drop rollers 165, 166, said sheet is engaged between feed and drop 15 rollers 193, 194 that feed the sheet across the table 174 into engagement with movable front stops 195 (Figs. 1, 3, 7, 10 and 11) that stop the sheet and enable it to be registered by hand with the trimmer 175. The feed rollers 193 project 20 slightly above the top of the support or die plate 174 through openings 196 therein (Figs. 2 and 6). The feed rollers 193 are fixed on a shaft 197 (Figs. 3 and 10) journaled in suitable bearings 25 at the rear of the support 174 and on the underside thereof. Fixed on the shaft 197 and extending in a suitable opening in the underside of the support 174, is a pulley 198 (Fig. 3) around which passes a belt 199 that serves to drive the shaft 197 and the feed rollers 193 thereon. The belt 30 199 passes around an idler pulley 200 and around a driven pulley 201. The driven pulley 201 is loosely mounted on a stub shaft 202 carried by a bracket 203 which carries the bracket 191. The bracket 203 depends from and is secured to the 35 table or die plate 174 and carries the idler pulley 200. Secured to or formed integrally with the pulley 201 is a sprocket 204 around which passes a chain 205. The chain 205 also passes around a sprocket 206 which is fixed on the shaft 40 40 to rotate therewith. It will appear, from the foregoing, that the feed rollers 193 are driven from the shaft 40 of the sheet feeding mechanism through the described connections for said shaft with the shaft 197 that carries said rollers.

Rollers 194 are journaled on long bent arms 45 207 which are fixed on a rockshaft 208 (Figs. 2a, 3 and 6). Each of the arms 207 is preferably made in two parts pivotally and adjustably connected together at 209 and 210, respectively. The rockshaft 208 is journaled in suitable bearings 50 on the frames 29 and extends transversely thereof. Fixed on the rockshaft 208 is an arm 211 (Fig. 6) on the free end of which is journaled a roller 212. This roller 212 extends under and 55 is engaged by cam 213 that is fixed on the cam shaft 68. It will appear, from the foregoing, that the drop rollers 194 are raised and lowered by the cam 213 and act, in conjunction with the feed rollers 193 to feed the sheets successively 60 over the table or trimmer die plate 174 to the sheet stops 195 at the front thereof.

The sheet stops 195 are moved upwardly to stop each sheet on the table 174 and after the sheet 65 has been registered and trimmed, said stops move downwardly and the sheet is delivered by mechanism to be hereinafter described. The stops 195 are preferably mounted and operated as follows. Journaled in suitable bearings on the under forward portion of the table 174 is a rockshaft 214 (Fig. 11). This rockshaft has fixed thereon sleeves 215 within which are slidably mounted rods 216 that carry the stops 195. The rods 216 are prevented from rotating in the sleeves 215 by screws 216' engaged in key-ways 216'' of said rods. The rods 216 and the stops 105 may thus be

adjusted longitudinally of the sleeves 215, as by adjusting screws 217 housed in extensions 218 of said sleeves and having threaded engagement with the shafts 216. When the rods 216 have been adjusted, they are locked by nuts 217' threaded thereon to bear against the sleeves 215. Fixed on the rockshaft 214 is an arm 219 pivotally connected with one end of a link 220. The opposite end of the link 220 is pivotally connected with an arm 221 that is fixed on a rockshaft 222. This rockshaft 222 is journaled in suitable bearings on the frames 29 and extends transversely thereof. Fixed on the rockshaft 222 is an arm 223. The arm 223 has journaled thereon a roller 224 that engages a cam 225 that is fixed on the cam shaft 68. The arm 223 has pivotally connected therewith one end of a spring pressed rod 226. The opposite end of the rod 226 is slidably guided at 226' on one of the side plates 41. It will appear, from the foregoing, that the rock shaft 222 is cam-operated in one direction and spring-operated in the opposite direction, and that when said shaft is rocked it acts, through the described connections therefor with the stops 195 to raise and lower the same as aforesaid.

The sheet trimming mechanism may be of any suitable construction but as herein shown said mechanism is preferably operated and constructed as follows. Fixed on the shaft 22 is a pulley 227 (Fig. 1) around which passes a belt 228. The belt 228 also passes around a pulley 228' that is loosely mounted on a shaft 229. This shaft 229 is journaled in suitable bearings on a head 230 (Fig. 7) that overhangs the support 174 and is secured to or formed integrally with the column 105 231 previously referred to. The column 231, in turn, is secured to or formed integrally with the pedestal 18 and extends upwardly therefrom in spaced relation with the column 192. Secured to or formed integrally with the loose pulley 228' 110 is a friction clutch member 232 (Fig. 8) adapted to rotate loosely on the shaft 229 with said loose pulley. Extending over the clutch member 232 is a spring clutch member 233 that is secured to or formed integrally with a sleeve 234. The 115 sleeve 234 is keyed to and slidable along the shaft 229 and carries a collar 235 having an annular groove 236 into which projects a small roller 237. This roller 237 is journaled on the upper end of an arm 238 which is pivoted at 239 on the head 120 230. The arm 239 has secured to or formed integrally therewith a second arm 240 which extends substantially at right angles to the arm 238 and is pivotally connected with the upper end 125 of a rod 241. The rod 241 extends downwardly through suitable openings formed in spaced brackets 242 and 243 (Fig. 9) secured to or formed integrally with the column 231 and the pedestal 18, respectively. Mounted on the rod 241 between the brackets 242 and 243 is a spring 244 the lower end of which bears against the bracket 243. The upper end of the spring 244 bears against a collar 245 fixed on the rod 241 in spaced relation with the bracket 242. The spring 244 normally tends to move the rod 241 upwardly to hold 130 the clutch parts 232, 233 in disengaged relation.

Fixed on the rod 241 below the bracket 243 is a keeper 246 that is engaged by a latch 247. This latch 247 is secured to or formed integrally with a lever 248 having connected therewith one end of a spring 249. The opposite end of the spring 249 is connected with a bracket 250 secured to or formed integrally with the pedestal 18. The spring 249 serves to maintain the latch 247 in engagement with the keeper 246, and the lever 248, 145

which carries said latch, is pivoted at 251 on a block 252 which is secured to or formed integrally with a long lever 253. The block 252 is provided with a shoulder 254 that limits movement 5 of the lever 248 imparted thereto by the spring 249 to hold the latch 247 in engagement with the keeper 246. The lever 253 is pivoted at 255 on the bracket 250, and pivotally connected with said lever, as at 256, is a yoke 257 the arms of which 10 have trunnioned therein the lower end of a rod 258. Mounted on the rod 258 is a spring 259 the lower end of which bears against an abutment 260. The upper end of the spring 259 bears against a collar 261 that is fixed on the rod 258. 15 The upper end of the rod 258 is pivotally connected with the forward free end of the lever 180. Said end of the lever 180 also has connected therewith the lower extremity of the spring 262 (Fig. 7). The upper extremity of the spring 262 20 is secured to the hook 263 which projects outwardly from and is secured to the column 231, as previously described.

The lever 180 is provided intermediate its opposite ends with an enlarged portion 264 in 25 which is formed an arcuate-shaped slot 265 through which passes the feeder controlling rockshaft 51. This slot 265 provides for rocking movement of the arm 180 imparted thereto by the cam 176 and the spring 262. The rocking arm 180 acts, through the described connection 30 therefor with the rod 241, to move the latter up and down and swing the arm 238 about its pivot 239. When the arm 238 is swung to the left (Fig. 7) a detent 266 pivoted at 267 on said arm 35 passes over a shoulder 268 on a bent lever 269 and swings the latter downwardly. This lever 269 is pivoted at 270 on the bearing for shaft 229, and downward swinging movement of said lever is limited by a pin 271 secured to the arm 40 238. When the lever 269 is swung downwardly the notched end 272 thereof is disengaged from a shoulder 273 on the clutch part 233 and the latter is engaged with the clutch part 232 by the arm 238. The lever 269 is guided in a slot 274 45 formed in the upper end of the column 231, and when the clutch parts 232, 233 are connected, the shaft 229 is operated and the trimmer 175 descends and trims the money or other sheet that has been delivered onto the support or 50 trimmer die plate 174 by the described means for this purpose.

The trimmer 175 is of rectangular formation 55 adapted to trim the sheet on all four sides thereof, and said trimmer is mounted and operated as follows. Secured to or formed integrally with the shaft 229 at the end thereof opposite that carrying the pulley 228', is an eccentric pin 275 on which is mounted a block 276. This block 276 is slidably received in a horizontally extending 60 elongated guide opening 277 of a head 278 that is secured to or formed integrally with a vertically movable slide 279. The slide 279 is guided vertically in the slot 280 of a guide 281, secured to or formed integrally with the overhanging head 230. The slide 279 is retained in the slot 65 280 of guide 281 by a plate 282 secured to said guide, as by machine screws 283. Secured to or formed integrally with the slide 279, at the end thereof below the guide 281, is a bail 284. This 70 bail has secured to or formed integrally therewith a horizontally arranged rectangular frame 285 on the four sides of which are secured the blades 286 of the trimmer 175. The bail 284 has formed in the upper part thereof a vertical guide 287 75 for a slide 288 which is retained in said guide

by a plate 289 secured to the bail 284, as by machine screws 290.

Secured to, or formed integrally with, the slide 288 is a second bail 291. This bail 291 has secured to the arms thereof a horizontally arranged rectangular guard 292. When the clutch parts 232, 233 are connected, as above described, the shaft 229 is rotated a single revolution, and the connections for said shaft with the bail 284 cause the trimmer 175 to descend and trim the sheet on the trimmer die plate 174 and then move upward therefrom. When the trimmer 175 descends, the guard 292 rests on the trimmer die plate 174 and prevents the operator from coming in contact with the trimming knives 286. 80 The table or trimmer die plate 174 has pivoted thereon a circular plate 293 in the center of which is a cross mark 294. This cross mark 294 registers with a pointer 295 which is fixed on a shaft 296 journaled in suitable bearings on the frame 285 and extending transversely thereof. Fixed on the shaft 296 in spaced relation with the pointer 295 are other pointers 297. The ends of all the pointers above referred to are arranged in a straight line, and previous to descent of the 90 trimmer 175, the sheet is delivered onto said support under said pointers and there stopped by the sheet stops 195. In the case of sheets of money, each of the same has a plurality of notes printed thereon and sight marks at the center 95 of the sheet.

When the sheet is stopped on the trimmer die plate, the trimmer is in its uppermost position, and the machine attendant sight registers the marks on the sheet with the pointers 295, 297, 100 The machine attendant is required to perform this operation in the shortest possible time for the reason that the described connections between the feeder and the trimmer are timed so that the latter descends almost immediately after 105 the sheet has been delivered onto the trimmer die plate. The sheet having been sight registered, the trimmer 175 descends and trims the sheet on all four sides thereof. When the trimmer 175 descends, cutters 175' (Figs. 1, 2 and 7) on diagonally opposite corners thereof, cut the trimming at its corresponding diagonally opposite corners. The cutters 175' cooperate with cutters 175'' which are carried by the trimmer die plate 174 and provide therewith spaces 175''' to receive 120 the trimmer 175 when the latter is lowered. When the trimmer 175 descends, the support 167 is lowered by the arm 180, and the trimmed and diagonally cut portions of the sheet fall clear of the trimming mechanism, the pedestal 18, and 130 other parts of the machine. Thereafter, the support 167 and the trimmer move upwardly and another sheet is delivered onto the trimmer die plate to be stopped, sight registered, and trimmed thereon, as in the case of the first sheet. 135 These operations are repeated in a substantially continuous manner as the sheets are delivered successively onto the trimmer die plate by the described means for this purpose.

During one revolution of the shaft 229 the 140 trimmer 175 is moved downwardly and then upwardly, whereupon the low part of the cam 176 moves opposite the roller 177 and the spring 262 acts to raise the arm 180 which, in turn, raises the support 167. As the arm 180 is raised, the 145 connections therefor with the arm 240 swings the arm 238 to the right (Fig. 7) whereupon the clutch parts 232, 233 are disengaged by said arm and the pin 271 engages and raises the lever 269 which acts, through engagement of the 150

notched end 272 thereof with the abutment 273, to stop rotation of the clutch part 233 and the shaft 229 after the same have made one revolution. It will appear, from the foregoing, that the operation of the trimmer is controlled automatically by the sheet feeding mechanism, and that the machine attendant is required to sight register the sheets as fast as they are delivered onto the table or trimmer die plate, in order that they may be trimmed thereon and delivered from said die plate by mechanism which will now be described. It will further appear, that by changing the size of the sprocket 25 from time to time, without the knowledge of the attendant, the sheet feeding and trimming mechanisms may be speeded up so that the machine attendant is required to perform his or her duties at correspondingly increased speed.

Secured to or formed integrally with the loose pulley 228' is a pulley 298 around which there passes a belt 299. This belt 299 passes downwardly around a pulley 300, then upwardly around pulleys 301 and 302 (Figs. 1, 2 and 7). From the pulley 302 the belt 299 passes downwardly around a pulley 303, then upwardly around a pulley 304, and then downwardly around a pulley 305 (Fig. 1). From the pulley 305, the belt passes upwardly over a pulley 306 and around the pulley 298 to the previously mentioned pulleys. The pulleys 300 and 302 are preferably formed integrally with each other, and are journaled, with the pulley 306, on an arm 307 that projects from the column 231 and is secured thereto in any suitable manner. The pulley 301 is fixed on a shaft 308 that is journaled in suitable bearings in brackets 309 that are bolted or otherwise suitably secured on the side of an inclined delivery box 310 (Figs. 1 and 2). The box 310 is secured at 311 on the upper end of a pedestal 312 that is bolted or otherwise suitably secured at 313 to the base plate 7. The pulley 304 is secured on a shaft 314 that is journaled in suitable bearings on the table or trimmer die plate 174 at the under forward portion thereof. The pulleys 303 and 305 are preferably formed integrally with each other in spaced relation, and said pulleys are journaled on a stub shaft 315 carried by the pedestal 18.

It will appear, from the foregoing, that the belt 299 continuously drives the shafts 308 and 314. These shafts have fixed thereon feed rollers 316 and 317, respectively, the rollers 317 and the pulley 304 projecting upwardly through openings 318 formed in the support or trimmer die plate 174 at the forward end thereof (Figs. 1, 2, 7 and 10). The brackets 309 have journaled therein above the rollers 316 a shaft 319 on which are fixed rollers 320 that cooperate with the rollers 316. The rollers 317 and drop rollers 321 cooperating therewith serve to feed the trimmed sheets successively between the rollers 316, 320, under a guard 322 and into the delivery box 310. The guard 322 is pivoted on the shaft 319, and the forward end of said guard rests on the lower forward end of said delivery box.

The drop rollers 321 are operated in timed relation with the trimmer to feed each sheet therefrom into the delivery box when the trimmer is raised. Said drop rollers are preferably operated and mounted as follows. Pivots connected with the lever 248 and reciprocated thereby, is a rod 323 (Figs. 7 and 9). This rod 323 is also pivotally connected with an arm 324 that is pivoted at 325 on the column 231. Secured to the arm 324 on the free end thereof are leaf

springs 326 that project through a vertically extending elongated slot 327 formed in a clevis 327' that is pivotally mounted on an arm 328. The arm 328 is pivoted on the bail 284 and connected therewith by a spring 329. The arm 328 extends through a guide 330 that is secured to the slide 288, and said arm has secured to the forward end thereof a downwardly projecting fork 331 that extends over the feed rollers 317 and carries the drop rollers 321 which cooperate therewith.

When the lever 253 is moved downwardly to connect the clutch 232, 233, and cause the trimmer 175 to descend, the arm 324 is also moved downwardly by the rod 323 and the leaf springs 326 move downwardly toward, but in spaced relation with, the lower end of the slot 327 formed in clevis 327'. The guard 292 descends and rests on the sheet and support 174, but the trimmer 175 continues to descend to trim said sheet on all four sides thereof and the cutters 175' sever the unbroken trimmed margin at diagonally opposite corners of the same. This relative movement between the guard 292 and the trimmer 175, enables the spring 329 to lift the arm 328 in the guide 330 so that the drop rollers 321 are raised out of engagement with the sheet and the feed roller 317. When the trimmer is raised, however, the guard 292 drops slightly and causes the arm 328 to swing downwardly so that the drop rollers 321 are engaged with the trimmed sheet and the feed rollers 317 thereupon act to feed said sheet between the rollers 316, 320 into the delivery box 310. When the drop rollers lower, the arm 328 engages the springs 326 which, upon being lifted by the lever 253 and the rod 323 raise the guard 292 with the bail 284 and the trimmer 175 carried thereby. It will appear from the foregoing, that each time the trimmer is lowered the drop rollers 321 are raised, and that each time the trimmer is raised said drop rollers are lowered, the operation being such that the successively trimmed sheets are successively delivered from the trimming mechanism to the delivery box as before described. When the trimmer is raised and the drop rollers are lowered, the latter engage the wheels 317 a sufficient length of time to deliver the trimmed sheet, whereupon said drop rollers rise to inoperative positions early enough to prevent interference thereof with the entry of the next sheet.

Under normal conditions, the feeding, trimming, and delivery of the sheets are accomplished automatically and in a substantially continuous manner, and the trimming mechanism and other described mechanisms are controlled by the sheet feeding mechanism. It sometimes happens, however, that the attendant's services are required elsewhere, or that an emergency arises that requires stopping of the sheet feeding and trimming mechanism. Accordingly, said mechanisms are preferably provided with control devices and said devices are preferably mounted and operated as follows. Bolted or otherwise suitably secured, as at 332, to the base 18' of the pedestal 18 is a bracket 333 on the upper end of which is pivoted a lever 334 having an axis of rotation extending substantially at right angles to that of the lever 253 (Fig. 9). This lever 334 has secured thereto a short foot pedal 335 extending in parallel relation with a long foot pedal 336 that is secured to the lever 253. These pedals 335, 336 are provided with foot plates 337 and 338, respectively, and the lever 334 is connected with the lower end of a spring 339 whose upper

end is connected with the bracket 333 adjacent the pivot for said lever thereon. The spring 339 normally tends to swing the lever 334 and the foot pedal 335 outwardly so that a stop 340 on 5 said lever is removed from the path of movement of the lever 253. Assuming that a sheet has been delivered onto the table or trimmer die plate 174 and that the machine attendant's attention is required for some duty other than sight 10 registering the sheet, the attendant depresses the pedal 335 thus bringing the stop 340 under the lever 253 and stopping the operation of the trimming mechanism. The untrimmed sheet on the table or trimmer die plate 174 then prevents 15 a detector finger 341 (Figs. 3 and 7) from moving downwardly into an opening 342 in the trimmer die plate 174. The detector 341 then acts, through mechanism which will now be described, to stop the sheet feeder and prevent it 20 from feeding any more sheets to the trimming mechanism until the operator has released the foot pedal 335, and depressed the pedal 336 downwardly to connect the trimmer clutch and trim the sheet on the trimmer die plate.

25 The detector finger 341 is secured to or formed integrally with an arm 343 (Fig. 3) which is fixed on a rockshaft 344 journaled in suitable bearings on arms 345 and the side plates 41. The arms 345 carry supports 346 for resilient stops 30 346' which limit the upward swinging movement of the support 167, and said arms are fixed on a stay shaft 347 extending transversely of the frames 29 and secured thereto in any suitable manner. The stay shaft 347 also has fixed thereon supports 348 for top rods 349 which extend 35 over the bridge pieces 167" and the support 167 and prevent upward displacement of the sheets as they are fed across said bridge pieces and said support to the sheet trimming mechanism.

40 The sheets pass under the detector 341 to lift it and rock the shaft 344 in one direction, and the detector 341 drops into the opening 342 after delivery of each sheet from the plate 174 and rocks the shaft 344 in the opposite direction.

45 With the sheet trimming mechanism stopped and a sheet in position on the trimmer die plate 174, however, the detector 341 is prevented from dropping into the opening 342, and an arm fixed on the shaft 344, and normally rocking therewith, fails to move into the path of travel of a 50 detent 351 secured to or formed integrally with a rocking arm 352. The arm 352 is loosely mounted on a shaft 353 extending transversely of the frames 29 and journaled in suitable bearings 55 thereon. The shaft 353 has fixed on one end thereof a handle 354 for rocking the shaft to control the valve mechanism in the housing 137.

Under normal operating conditions, the arm 60 352 is rocked by the high part only of a cam 355 that is fixed on the cam shaft 68. The arm 352 is rocked in the opposite direction by a spring 356 having one extremity secured to said arm and its opposite extremity secured to one of the plates 41. Pivotaly connected with the arm 352 65 is a rod 357 the lower slotted end 358 of which is engaged over a pin 359 carried by an arm 360. The arm 360 is fixed on the feeder control shaft 51 and said arm has connected therewith one extremity of a spring pressed rod 361 the opposite extremity of which is guided on the adjacent side plate 41. The rod 361 normally tends to swing the arm 360 upwardly and maintain the clutch spreader 56, 57 out of engagement with the clutch parts 47, 48 so that said parts are 70 connected by the spring 49 to drive the pile eleva-

tor and the sheet engaging devices associated therewith through the means previously described for this purpose.

When a sheet is stopped on the die plate 174, the arm 350 fails to move into the path of travel of the detent 351, and the spring 356 pulls the arm 352 downwardly so that the cam engaging roller 362 thereon follows the low part of the cam 355 and the rod 357 is pushed downwardly to rock the arm 360 in the same direction. This downward motion of the arm 360 swings the shaft 51 so that the clutch spreader 56, 57 engages and spreads the clutch parts 47, 48, and thus stops the drive for the pile feeder and associated devices.

90 Fixed on the clutch throw-out shaft 51 is an arm 363 (Figs. 3 and 9) that is pivotally connected with the upper end of a link 364. The lower end of the link 364 is pivotally connected with an arm 365 that is fixed on a stub shaft 366 journaled in a bracket 367. The bracket 367 is bolted or otherwise suitably secured at 368 to the bed plate 7, and fixed on the stub shaft 366 is a second arm 369 provided at its free end with a detent 370 that is normally engaged with a spring pressed latch 371. The latch 371 is pivotally mounted at 372 on the long lever 336, and the spring for said latch is indicated at 373.

95 When the detector 341 and the arm 352 stop the feeder, as above described, the arm 363 is moved upwardly and acts, through the described connections therefor with the shaft 366, to rock the arm 369 downwardly and disengage the detent 370 from the latch 371. Assuming now, that the attendant proceeds with the operation of 100 sight registering a sheet and completes said operation, the short foot pedal 335 is released and the spring 339 rocks said lever so that the stop 340 is disengaged from and moved out of the normal path of movement of the lever 253. The attendant then presses the long foot pedal 336 downwardly to connect the clutch parts 232, 233 so that shaft 229 is operated and the trimmer trims the sheet that has been stopped on the trimmer die plate 174.

105 The attendant then further presses the lever 336 downwardly so that the latch 247 rides downwardly over the keeper 246 and the latch 371 is reengaged with the detent 370. The attendant thereupon releases the lever 336 and the latter 110 moves upwardly and the sheet trimming mechanism is thereafter operated automatically, as before described. At the same time, the lever 336 on moving to normal operating position, moves the arm 369 upwardly and said arm, through the described connections therefor with the arm 363, operates the shaft 51 to remove the clutch spreader from the clutch parts 47, 48. Said parts are 115 then engaged by the spring 49 to start the feeder which then feeds the sheets successively to the sheet trimming mechanism. The latter trims the sheets successively as they are sight registered in like manner, and said sheets are delivered one after another from the trimming mechanism into the delivery box 310, as before described.

120 It will appear, from the foregoing, that mechanism constructed and associated in accordance with the present invention will automatically feed, trim, and deliver sheets without the necessity for manual controls, and with the resulting increased 125 production and efficiency of the trimming plant and personnel therefor. Moreover, in the case of trimming sheets of money, the attendant is relieved from the various duties in connection with 130 operation of manual controls, and is only required 135 140 145 150

to sight register the sheets with the trimmer as fast as they are delivered thereto from the sheet feeder. In this way, the attendant is required to keep the speed of sight registering up to the speed of delivery and trimming, and thus insure maximum production of the trimming plant under ordinary operating conditions thereof. Further, in the case of experienced or inexperienced attendants, the sheet feeding and trimming mechanisms

10 may be gradually speeded up without their knowledge until both the mechanisms and the attendants therefor are brought up to maximum efficiency.

While one embodiment of the invention has been illustrated and described with more or less particularity, it is to be expressly understood that the invention is not limited to said embodiment nor otherwise than by the terms of the appended claims.

20 What we claim is:

1. In apparatus of the character described, means for supporting and feeding a supply of sheets, means for separating and forwarding sheets successively from said supply, mechanism for operating the aforesaid means, sheet trimming means to which the sheets are delivered successively from the separating and forwarding means, mechanism for operating the sheet trimming means and including a driven element and a clutch adapted to connect and disconnect said element relative to said sheet trimming means, and clutch operating connections between said first named mechanism and the clutch and timing the operation of said clutch and the sheet trimming means so that the latter trims each sheet delivered thereto from said sheet separating and forwarding means.

2. In apparatus of the character described, means for supporting and feeding a pile of sheets upwardly step by step, means for separating and forwarding sheets successively from the top of said pile, mechanism for operating the aforesaid means, reciprocating sheet trimming means to which the sheets are delivered successively from the sheet separating and forwarding means, mechanism for operating the sheet trimming means and including a driven element and a clutch adapted to connect and disconnect said element relative to said sheet trimming means, and clutch operating devices connecting said clutch and said first named mechanisms together and timing the operation of the clutch and said reciprocating sheet trimming means so that the latter trims each sheet delivered thereto from said sheet separating and forwarding means.

3. In apparatus of the character described, means for supporting and feeding a supply of sheets, means for separating and forwarding sheets successively from said supply, mechanism for operating the aforesaid means, intermittently operated sheet trimming means to which the sheets are delivered successively from the sheet separating and forwarding means, mechanism for intermittently operating the sheet trimming means and including a driven element and a clutch adapted to connect and disconnect said element relative to said sheet trimming means, and clutch operating means interconnecting the clutch and said first-named mechanisms and actuated thereby to intermit the operation of said clutch and said sheet trimming means so that the latter trims each sheet delivered thereto from said sheet separating and forwarding means.

4. In apparatus of the character described, in-

feeding a supply of sheets, continuously operated means for separating and forwarding sheets successively from said supply, mechanism for operating the aforesaid means, reciprocating sheet trimming means to which the sheets are delivered successively from the sheet separating and forwarding means, devices for intermittently reciprocating the sheet trimming means and including a crank shaft connected therewith, a driven element loosely mounted on the crank shaft, and a clutch adapted to connect and disconnect said element relative to said crank shaft, and clutch operating means operated by said mechanism and timing the operation of said clutch so that the sheet trimming means is actuated to trim each sheet delivered thereto from said sheet separating and forwarding means.

5. In apparatus of the character described, means for supporting and feeding a supply of sheets, means for separating and forwarding sheets successively from said supply, mechanism for operating the aforesaid means, sheet trimming means to which the sheets are delivered successively from the sheet separating and forwarding means, mechanism for intermittently operating the sheet trimming means and including a driven element and a clutch adapted to connect said element with and disconnect the same from said sheet trimming means, and devices operated by said first named mechanism and adapted to actuate said clutch so that the trimming means operates to trim each sheet delivered thereto from said sheet separating and forwarding means.

6. In apparatus of the character described, sheet feeding means, means for trimming sheets successively delivered thereto from the sheet feeding means, mechanism for intermittently operating the sheet trimming means, a clutch for connecting said mechanism with and for disconnecting the same from the sheet trimming means, and devices operated by the sheet feeding means and actuating said clutch so that the sheet trimming means is connected with its operating mechanism each time a sheet is delivered to said sheet trimming means from said sheet feeding means.

7. In apparatus of the character described, sheet feeding means, a table or die plate onto which sheets are delivered successively from the sheet feeding means, a trimmer movable toward and away from the table or die plate and adapted to trim each sheet delivered thereto on all four sides thereof, clutch controlled mechanism for operating the trimmer, and automatically actuated clutch operating devices for the clutch of said mechanism and timing the operation thereof so that said trimmer trims each sheet delivered onto said table or die plate from said sheet feeding means.

8. In apparatus of the character described, sheet feeding means, mechanism for operating the sheet feeding means and including a driven shaft having a cam thereon, sheet trimming means adapted to trim sheets successively delivered thereto from said sheet feeding means, mechanism for operating the sheet trimming means and including a driven element and a clutch adapted to connect and disconnect said element relative to said sheet trimming means, a lever operated by said cam, and devices operated by said lever and actuating the clutch of said last named mechanism at predetermined intervals.

9. In apparatus of the character described,

- sheet feeding means, mechanism for operating the sheet feeding means including a driven shaft, sheet trimming means adapted to trim sheets successively delivered thereto from said sheet-feeding means, mechanism for operating the sheet trimming means, a clutch controlling the operation of said last named mechanism, devices for operating said clutch, a lever for operating said devices, and a cam on said shaft and adapted to operate said lever.
10. In apparatus of the character described, sheet feeding means, a table or die plate onto which sheets are successively delivered from the sheet feeding means, a trimmer movable toward 15 and away from the table or die plate and adapted to trim each sheet delivered thereto on all four sides thereof, mechanism for operating said trimmer, a clutch controlling the operation of said mechanism, clutch operating means, and 20 means operated by the sheet feeding means and connected with said clutch operating means to automatically actuate the same.
11. In apparatus of the character described, sheet feeding means, mechanism for operating 25 the sheet feeding means and including a driven shaft having a cam thereon, a table or die plate onto which sheets are delivered successively from the sheet feeding means, a trimmer movable toward and away from the table or die plate and 30 adapted to trim each sheet delivered thereto on all four sides thereof, mechanism for operating said trimmer, a clutch controlling the operation of said last named mechanism, clutch operating means, and a lever operated by said cam and 35 connected with said clutch operating means to automatically actuate the same.
12. In apparatus of the character described, sheet feeding means, sheet trimming means adapted to trim sheets successively delivered 40 thereto from the sheet feeding means, and a device movable in one direction to support each sheet as it is being delivered to the sheet trimming means and movable in the opposite direction to facilitate removal of waste portions of 45 each sheet trimmed by said sheet trimming means.
13. In apparatus of the character described, sheet feeding means, sheet trimming means adapted to trim sheets successively delivered 50 thereto from the sheet feeding means, a pivoted element movable in one direction to support each sheet as it is being delivered to the sheet trimming means and movable in the opposite direction to facilitate removal of waste portions of 55 each sheet trimmed by said sheet trimming means, and means for rocking said element in opposite directions.
14. In apparatus of the character described, sheet feeding means, sheet trimming means adapted to trim sheets successively delivered 60 thereto from the sheet feeding means, a device interposed between said means and movable in one direction to support each sheet as it is being delivered to the sheet trimming means and 65 movable in the opposite direction to facilitate removal of waste portions of each sheet trimmed by said sheet trimming means, and connections between said sheet feeding means and said device for operating the latter.
- 70 15. In apparatus of the character described, sheet feeding means, sheet trimming means adapted to trim sheets successively delivered thereto from the sheet feeding means, a device movable in one direction to support each sheet 75 as it is being delivered to the sheet trimming means and movable in the opposite direction to facilitate removal of waste portions of each sheet trimmed by said sheet trimming means and movable in the opposite direction to facilitate removal of waste portions of each sheet trimmed by said sheet trimming means, and means controlling the operation of the sheet trimming means and connected with said device to operate the same.
16. In apparatus of the character described, sheet feeding means, a table or die plate onto which sheets are successively delivered from the sheet feeding means, a device movable into and out of the plane of the table or die plate to support each sheet as it is being delivered thereto and to facilitate removal of waste portions of sheets trimmed thereon, means for moving said device into and out of the plane of the table or die plate, and a trimmer adapted to trim each sheet as it is delivered onto said table or die plate from said sheet feeding means.
17. In apparatus of the character described, sheet feeding means, movable means and stationary means over which sheets are successively delivered from the sheet feeding means, a trimmer adapted to trim each sheet as it is delivered over said stationary means, and means for moving said movable means into and out of the plane of the stationary means to support each sheet delivered thereto and facilitate removal of waste from each sheet trimmed thereon.
18. In apparatus of the character described, sheet feeding means, sheet trimming means adapted to trim sheets successively delivered thereto from the sheet feeding means, stationary bridge pieces and a movable plate over which the sheets pass successively, and means for operating said plate whereby it is moved in one direction to support each sheet delivered thereto and in the opposite direction to facilitate removal of waste portions of each sheet trimmed by said sheet trimming means.
19. In apparatus of the character described, sheet feeding means, a movable plate over which sheets are successively delivered by the sheet feeding means, trimming means arranged forwardly of the plate, means for feeding the sheets forwardly of the plate and successively to the sheet trimming means, mechanism for operating the sheet trimming means whereby it is caused to trim each sheet delivered thereto, and means for moving said plate into and out of operative position with respect to the sheet trimming means as each sheet is delivered thereto and trimmed thereby respectively.
20. In apparatus of the character described, sheet feeding means, sheet trimming means adapted to trim sheets successively delivered thereto from the sheet feeding means, a device movable in one direction to support each sheet as it is being delivered to the sheet trimming means and movable in the opposite direction to facilitate clearance of waste portions of each sheet trimmed by said sheet trimming means, mechanism controlling the operation of the sheet trimming means and including an element operated by the sheet feeding means, and connections between said element and said device for operating the same.
21. In apparatus of the character described, sheet feeding means, sheet trimming means adapted to trim sheets successively delivered thereto from the sheet feeding means, a pivoted plate movable in one direction to support each sheet as it is being delivered to the sheet trimming means and movable in the opposite direction to facilitate clearance of waste portions of each sheet trimmed by said sheet trimming means.

means, devices for controlling the operation of the sheet trimming means and including a lever operated by the sheet feeding means, and connections between said lever and said pivoted plate 5 for operating the latter.

22. In apparatus of the character described, sheet feeding means, sheet trimming means adapted to trim sheets successively delivered thereto, devices operated by the sheet feeding 10 means and controlling the operation of the sheet trimming means, and sheet advancing means operated by said sheet feeding means interposed between the sheet feeding and sheet trimming means, said sheet advancing means being adapted to deliver the sheets therefrom successively to 15 said sheet trimming means.

23. In apparatus of the character described, sheet feeding means, sheet trimming means adapted to trim sheets successively delivered 20 thereto, devices operated by the sheet feeding means and controlling the operation of the sheet trimming means, and feed and drop rollers operated by said sheet feeding means and adapted to deliver the sheets successively therefrom to said 25 sheet trimming means.

24. In apparatus of the character described, sheet feeding mechanism, a table or die plate, a trimmer adapted to trim sheets successively delivered on the table or die plate, means on said 30 table or die plate adapted to feed sheets successively thereover from the sheet feeding mechanism, and connections between said sheet feeding mechanism and said means for operating the latter therefrom.

25. In apparatus of the character described, sheet feeding mechanism, a table or die plate, a trimmer adapted to trim sheets successively delivered on the table or die plate, feed rollers on 40 the table, drop rollers cooperating with the feed rollers to feed sheets successively over said table or die plate from the sheet feeding mechanism, and means operated by said sheet feeding mechanism and adapted to operate said feed and drop rollers.

45. 26. In apparatus of the character described, sheet feeding mechanism, a table or die plate, a trimmer adapted to trim sheets successively delivered on the table or die plate, sheet advanced means on the table or die plate, and a drop roller 50 cooperating with the sheet advancing means to feed sheets successively from said sheet feeding mechanism onto said table or die plate.

27. In apparatus of the character described, sheet feeding mechanism, a table or die plate, a trimmer adapted to trim sheets successively delivered on the table or die plate, means adjacent one extremity of the table or die plate and adapted to deliver untrimmed sheets successively thereover from said sheet feeding mechanism, and 55 means adjacent the opposite extremity of said table or die plate and adapted to deliver trimmed sheets successively therefrom.

28. In apparatus of the character described, a first set of feed and drop rollers adapted to 60 receive and feed sheets one after another, a second set of feed and drop rollers receiving sheets successively from the first named set, sheet trimming means carrying the feed roller or rollers of said second set and successively receiving the sheets therefrom, and operating mechanism for the two sets of feed and drop rollers and adapted to alternate the feeding actions of said sets.

29. In apparatus of the character described, sheet feeding means, sheet trimming means adapted to trim sheets successively delivered 65

thereto from the sheet feeding means, sheet stops arranged to swing to operative and inoperative positions and thereby momentarily stop each sheet so that it may be trimmed by said sheet trimming means, and means adapted to oscillate 80 said sheet stops.

30. In apparatus of the character described, sheet feeding means, sheet trimming means receiving sheets successively delivered thereto from the sheet feeding means, pivotally mounted sheet 85 stops arranged to swing to operative and inoperative positions and adapted to momentarily stop each sheet so that it may be trimmed by said sheet trimming means, and means for oscillating said sheet stops in timed relation with the 90 sheet feeding and trimming means.

31. In apparatus of the character described, sheet feeding means, a support on which sheets are delivered successively from the sheet feeding means, a trimmer for trimming the sheets 95 successively on the support, sheet stops arranged to swing above the support in-advance thereof, and means operated by said sheet feeding means and adapted to swing said sheet stops above and below said support to stop and release the successive sheets for trimming by and delivery from 100 said trimmer.

32. In apparatus of the character described, sheet feeding means, a table or die plate onto which sheets are delivered successively from the 105 sheet feeding means, a trimmer movable toward and away from the table or die plate and adapted to trim the sheets successively thereon, sheet stops pivoted on the table or die plate and movable above and below the same, and means for 110 oscillating the sheet stops to engage said sheet stops with and disengage them from the successive sheets.

33. In apparatus of the character described, sheet feeding means, automatically operated 115 sheet trimming means receiving sheets successively from said sheet feeding means and adapted to trim each sheet on all four sides thereof, and devices automatically controlling the operation of the sheet trimming means and enabling each un- 120 trimmed sheet to be manually registered with respect thereto.

34. In apparatus of the character described, sheet feeding means, sheet trimming means receiving sheets successively therefrom and adapted 125 to trim each sheet on all four sides thereof, sheet registering means adjacent the sheet trimming means, and means for automatically actuating the sheet trimming means at predetermined intervals such that each untrimmed sheet delivered 130 from said sheet feeding means to said sheet trimming means may be manually registered relatively thereto with the aid of said sheet registering means.

35. In apparatus of the character described, 130 sheet feeding means, sheet feeding devices operated thereby and successively receiving sheets therefrom, sheet trimming means carrying parts of the sheet feeding devices and adapted to trim sheets successively received therefrom, sheet delivery means, and sheet feeding means arranged on the sheet trimming means in spaced relation with said sheet feeding devices adapted to feed the trimmed sheets successively from said sheet trimming means to said sheet delivery means. 140

36. In apparatus of the character described, sheet feeding means, feed and drop rollers for feeding sheets successively from the sheet feeding means, sheet trimming means carrying parts of said feed and drop rollers and adapted to trim 150

sheets successively received therefrom, sheet delivery means, and sheet feeding means arranged in spaced relation with said feed and drop rollers and adapted to feed the trimmed sheets successively from said sheet trimming means to said delivery means.

37. In apparatus of the character described, feed and drop rollers, a table or die plate carrying parts of the feed and drop rollers and over which sheets are successively fed thereby, a trimmer adapted to trim the sheets successively as they are fed in like manner over the table or die plate by the feed and drop rollers, sheet feeding rollers carried by the table or die plate in spaced relation with said feed and drop rollers and adapted to feed the trimmed sheets successively from said table and said trimmer, and delivery means successively receiving the trimmed sheets from said sheet feeding rollers and including opposed driven rollers between which the trimmed sheets pass.

38. In apparatus of the character described, sheet feeding mechanism, sheet trimming mechanism adapted to trim sheets successively delivered thereto from the sheet feeding mechanism, means operated by the sheet feeding mechanism and controlling the operation of the sheet trimming mechanism, and a manually operated device movable into and out of engagement with said means to control the operation thereof.

39. In apparatus of the character described, sheet feeding means, sheet trimming means adapted to trim sheets successively delivered thereto from the sheet feeding means, interconnected devices operated by the sheet feeding means and controlling the operation of the sheet trimming means, and a manually operated element movable into and out of engagement with one of said devices to control the operation of all of the same.

40. In apparatus of the character described, sheet feeding mechanism, sheet trimming mechanism, means operated by the sheet feeding mechanism and controlling the operation of the sheet trimming mechanism, a lever forming part of said means, and a pivoted manually operated element movable into and out of engagement with said lever to control the operation of said means.

41. In apparatus of the character described, sheet feeding mechanism, sheet trimming mechanism adapted to trim sheets successively delivered thereto from the sheet feeding mechanism, control mechanism for the sheet trimming mechanism and operated by the sheet feeding mechanism, a manually operated element controlling said control mechanism, and means controlling the sheet feeding mechanism and controlled by said element.

42. In apparatus of the character described, sheet feeding mechanism, sheet trimming mechanism adapted to trim sheets successively delivered thereto from the sheet feeding mechanism, control mechanism for the sheet trimming mechanism and operated by the sheet feeding mechanism, a manually operated element adapted to stop said control mechanism and said sheet trimming mechanism, and sheet controlled means adapted to stop said sheet feeding mechanism when the control and sheet trimming mechanisms are stopped.

43. In apparatus of the character described, sheet feeding mechanism, sheet trimming mechanism adapted to trim sheets successively delivered thereto from the sheet feeding mechanism, control means operated by the sheet feeding mechanism and controlling the operation

of the sheet trimming mechanism, a lever forming part of the control means and movable relative thereto, and control means for the sheet feeding mechanism adapted to be actuated by said lever when it is moved relative to said first named control means.

44. In apparatus of the character described, sheet feeding mechanism, sheet trimming mechanism adapted to trim sheets successively delivered thereto from the sheet feeding mechanism, control means operated by the sheet feeding mechanism and controlling the operation of the sheet trimming mechanism, an element movable to and from an inoperative position and adapted to stop the control means and the sheet trimming mechanism, a lever forming part of the control means and movable independently thereof to start the sheet trimming mechanism when said element is moved to its inoperative position, and means controlled by the lever and adapted to start the sheet feeding mechanism when said lever has been moved to start the sheet trimming mechanism.

45. In apparatus of the character described, sheet feeding means, sheet trimming means adapted to trim sheets successively delivered thereto from the sheet feeding means, mechanism controlling the operation of the sheet trimming means, and sheet controlled means controlling the operation of said sheet feeding means.

46. In apparatus of the character described, sheet feeding means, sheet trimming means adapted to trim sheets successively delivered thereto from the sheet feeding means, mechanism operated by the sheet feeding means and controlling the operation of the sheet trimming means, and sheet controlled means controlling the operation of said sheet feeding means.

47. In apparatus of the character described, sheet feeding means, sheet trimming means adapted to trim sheets successively delivered thereto from the sheet feeding means, sheet controlled means for stopping the sheet feeding means, manually operated means for starting and stopping the sheet trimming means, and means operated by said manually operated means and adapted to start the sheet feeding means after said sheet trimming means has been started.

48. In apparatus of the character described, sheet feeding means, sheet trimming means adapted to trim sheets successively delivered thereto from the sheet feeding means, sheet controlled means adapted to stop the sheet feeding means, manually operated means for starting and stopping the sheet trimming means, devices for resetting the sheet controlled means after the sheet feeding means has been stopped thereby, and mechanism operated by said manually operated means and adapted to start the sheet feeding means after said sheet trimming means has been started.

49. In apparatus of the character described, sheet feeding means, a table or die plate over which sheets are successively delivered from the sheet feeding means, a trimmer adapted to trim sheets successively on the table or die plate, a sheet controlled detector movable into and out of an opening in said table or die plate, and mechanism controlled by said detector and controlling the operation of said sheet feeding means.

50. In apparatus of the character described, sheet feeding means, a table or die plate over which sheets are delivered successively from the

- sheet feeding means, mechanism for trimming the sheets successively on the table or die plate, devices operated by the sheet feeding means and controlling said mechanism, manually operated means controlling the operation of said devices, a sheet controlled detector movable into and out of an opening in the table or die plate, and mechanism controlled by said detector for controlling the operation of said sheet feeding means. 5
- 10 51. In apparatus of the character described, sheet feeding means, a table or die plate over which sheets are delivered successively from the sheet feeding means, a trimmer movable toward and away from the table or die plate and adapted to trim the sheets successively thereon, mechanism for operating the trimmer, devices operated by the sheet feeding means and controlling the operation of said mechanism, a lever movable into and out of engagement with one of 15 said devices to stop and start the latter and said trimmer, a sheet controlled detector movable into and out of an opening in said table or die plate, mechanism controlled by said detector and adapted to stop the sheet feeding 20 means, and means controlled by said lever and adapted to start said sheet feeding means when the lever is moved to start the trimmer. 25
52. In apparatus of the character described, sheet trimming means adapted to trim sheets successively fed thereto, a device movable in one 30 direction to guide each sheet to the sheet trimming means and movable in the opposite direction to facilitate removal of waste portions of each sheet trimmed by the sheet trimming means, and means for operating said device once during each cycle of operation of said sheet trimming means. 35
53. In apparatus of the character described, sheet trimming means adapted to trim sheets successively fed thereto, a device movable in one 40 direction to guide each sheet to the sheet trimming means and movable in the opposite direction to facilitate removal of waste portions of each sheet trimmed by the sheet trimming means, means for operating the movable device once during each cycle of operation of said sheet trimming means, and stop means adjacent said device. 45
54. In apparatus of the character described, sheet trimming means adapted to trim sheets successively fed thereto, sheet stopping means adjacent one extremity of the sheet trimming means and movable in opposite directions to stop and release the successive sheets for trimming by and delivery from said sheet trimming means, and means adjacent the opposite extremity of the sheet trimming means and movable in opposite directions to guide or support the sheets delivered to the sheet trimming means and facilitate removal of waste portions of the sheets 55 trimmed thereby. 60
55. In apparatus of the character described, sheet trimming means, and sheet stopping means and sheet supporting means adjacent opposite extremities of said sheet trimming means respectively and both movable to operative and inoperative positions relative thereto. 65
56. In apparatus of the character described, sheet trimming means, sheet stopping means and sheet supporting means adjacent opposite extremities of said sheet trimming means respectively and both movable to operative and inoperative positions relative thereto, and other stop means adjacent said sheet guiding or supporting means. 70
57. In apparatus of the character described, sheet feeding means for delivering sheets one after another at predetermined intervals, sheet trimming means adapted to trim sheets successively delivered thereto from the sheet feeding means at said intervals, and sheet controlled means controlling the operation of said sheet trimming means. 75
58. In apparatus of the character described, sheet feeding means for delivering sheets one after another at predetermined intervals, sheet trimming means adapted to trim sheets successively delivered thereto from the sheet feeding means at said intervals, and sheet controlled means controlling the operation of said sheet trimming means and said sheet feeding means. 80
59. In apparatus of the character described, means for trimming sheets, means for feeding sheets successively thereto at predetermined intervals, and sheet controlled means controlling the operation of said sheet trimming means. 85
60. In apparatus of the character described, means adapted to trim a sheet on all four sides thereof, means for feeding sheets successively thereto at predetermined intervals, and sheet controlled means controlling the operation of said first named means. 90
61. In apparatus of the character described, means adapted to trim a sheet along all four sides thereof, mechanism for automatically operating said means, means for feeding sheets successively to the trimming means at predetermined intervals, and sheet controlled means controlling the operation of said mechanism and said first named means. 95
62. In apparatus of the character described, means for feeding sheets successively at predetermined intervals, driven clutch controlled sheet trimming means to which sheets are fed one after another from the sheet feeding means at 100 said intervals, said sheet trimming means including a plurality of cutting edges for trimming off different marginal portions of a sheet, and automatically actuated clutch operating means for the clutch of the sheet trimming means and timing the operation thereof so that said cutting edges trim said marginal portions off each sheet fed to the sheet trimming means from said sheet feeding means. 110
63. In apparatus of the character described, means for feeding sheets successively at predetermined intervals, driven clutch controlled sheet trimming means to which sheets are fed one after another from the sheet feeding means at 115 said intervals, said sheet trimming means including a plurality of angularly related cutters for trimming off marginal portions of a sheet longitudinally and transversely thereof, and automatically actuated clutch operating means for the clutch of the sheet trimming means and timing the operation thereof so that said cutters trim said marginal portions off each sheet fed to the sheet trimming means from said sheet feeding means. 120
64. In apparatus of the character described, means for feeding sheets successively at predetermined intervals, reciprocating clutch controlled sheet trimming means to which sheets are fed one after another from the sheet feeding means at 130 said intervals, said sheet trimming means having a plurality of cutters for trimming off different marginal portions of a sheet, and automatically actuated clutch operating means for the clutch of the sheet trimming means and timing the operation thereof so that said cutters trim said marginal portions off each sheet fed to the sheet trimming means from said sheet feeding means. 135
65. In apparatus of the character described, means for feeding sheets successively at predetermined intervals, reciprocating clutch controlled sheet trimming means to which sheets are fed one after another from the sheet feeding means at 140 said intervals, said sheet trimming means having a plurality of cutters for trimming off different marginal portions of a sheet, and automatically actuated clutch operating means for the clutch of the sheet trimming means and timing the operation thereof so that said cutters trim said marginal portions off each sheet fed to the sheet trimming means from said sheet feeding means. 145
66. In apparatus of the character described, means for feeding sheets successively at predetermined intervals, reciprocating clutch controlled sheet trimming means to which sheets are fed one after another from the sheet feeding means at 150 said intervals, said sheet trimming means having a plurality of cutters for trimming off different marginal portions of a sheet, and automatically actuated clutch operating means for the clutch of the sheet trimming means and timing the operation thereof so that said cutters trim said marginal portions off each sheet fed to the sheet trimming means from said sheet feeding means. 150

simultaneously trim said marginal portions off each sheet fed to the sheet trimming means from said sheet feeding means.

65. In apparatus of the character described, 5 means for feeding sheets successively at predetermined intervals, a support for sheets fed there-to one after another from the sheet feeding means at said intervals, driven clutch controlled sheet trimming means movable toward and away 10 from the support to trim sheets thereon, said sheet trimming means having a plurality of cutting edges for trimming off different marginal portions of a sheet, and automatically actuated clutch operating means for the clutch of the 15 sheet trimming means and timing the operation thereof so that said cutting edges trim said marginal portions off each sheet fed to the sheet trimming means from said sheet feeding means.
66. In apparatus of the character described, 20 sheet trimming means including a plurality of cutters for trimming off different marginal portions of a sheet, means for feeding individual sheets successively to the sheet trimming means, and mechanism for operating said means in 25 timed relation such that said cutters trim said marginal portions off each sheet fed to the sheet trimming means from the sheet feeding means.

67. In apparatus of the character described, sheet trimming means including a plurality of angularly related cutters for trimming off marginal portions of a sheet longitudinally and transversely thereof, means for feeding individual sheets successively to the sheet trimming means, and mechanism for operating said means in timed relation such that said cutters trim said marginal portions off each sheet fed to the sheet trimming means from the sheet feeding means.

68. In apparatus of the character described, a die and sheet trimming means movable toward and away from the same, said die and trimming means being formed to trim an individual sheet within and around the entire marginal portion thereof, means for feeding individual sheets successively to the die and trimming means, and mechanism for operating the feeding and trimming means in timed relation such that each individual sheet fed by the feeding means to the die and trimming means is trimmed by the latter within and around the entire marginal portion of the sheet.

EDWARD R. KAST.
JOHN H. McELROY.
